UNITED STATES PATENT OFFICE

103,268

DESIGN FOR A DRESS

David William Price, New York, N. Y.

Application January 5, 1937, Serial No. 66,890

Term of patent 3½ years

To all whom it may concern:

Be it known that I, David William Price, a citizen of the United States of America, residing in Manhattan, county of New York, and State of New York, have invented a new, original, and ornamental Design for a Dress, of which the following is a specification, reference being had to the accompanying drawing, forming part thereof, wherein,

The design is characterized by an arrangement of lattice work embroidery on the collar and yoke portions of the dress as shown, which embroidery is offset at the shoulders by intersecting tucks, as shown.

I claim:

The ornamental design for a dress, substantially as shown, and described.

DAVID WILLIAM PRICE,
